UNITED STATES PATENT OFFICE.

WILLIAM FERDINAND PETERSEN, OF CHICAGO, ILLINOIS, ASSIGNOR TO PETERSEN
OVEN COMPANY, OF CHICAGO, ILLINOIS, A CORPORATION OF ILLINOIS.

BAKER'S OVEN.

1,197,393.

Specification of Letters Patent. Patented Sept. 5, 1916.

Application filed June 14, 1915. Serial No. 33,899.

To all whom it may concern:

Be it known that I, WILLIAM FERDINAND PETERSEN, a citizen of the United States, residing at Chicago, in the county of Cook and State of Illinois, have invented new and useful Improvements in Bakers' Ovens, of which the following is a full, clear, and exact description.

My invention relates to bakers' ovens, and particularly to ovens in which the pans are carried into and out of the baking-chamber by a suitable conveyer.

The object of my invention is to prevent the loss of heat due to the cooling of the trays upon which the pans are placed, the chains and other parts of said conveyer when the same is withdrawn from the baking-chamber, and thus greatly increase the efficiency of the oven because of the saving of time and fuel required to reheat the parts thereof.

A further object is to provide means for imparting heat to the baking-chamber in a more direct manner than has heretofore been done with ovens of this character, and to adopt novel construction that permits this to be done.

These I accomplish by the means herein-after fully described, and as particularly pointed out in the claims.

In the drawings: Figure 1 is a vertical longitudinal section of a baker's oven. Fig. 2 is a horizontal section thereof taken on dotted line 2—2, Fig. 1. Fig. 3 is a transverse vertical section of the same taken on dotted line 3—3, Fig. 1, looking in the direction indicated by the arrows. Fig. 4 is a vertical transverse section taken on dotted line 4—4, Fig. 1, looking in the direction indicated by the arrows. Fig. 5 is a fragmentary view showing a detail of the construction of the mechanism for suspending the trays from the conveyer chains, drawn to a larger scale. Figs. 6 and 7 are fragmentary views illustrating, respectively, transverse and longitudinal vertical sections of the chamber in which the rear guide-wheels for the conveyer chains are housed, and the chain tightening devices used in connection therewith.

While my invention can be used in bakers' ovens made practically entirely of brick and tile, I prefer to use a skeleton or framework for the same which is built up of commercial forms of rolled metal. As shown in the drawings, the oven is rectangular in shape, and at each corner has vertical posts 8, 8, which, above their base-plates, are of I-beam section. These posts 8, 8, are connected on each side of the furnace by an upper and a lower longitudinally disposed I-beam 9, 9, through the medium of metal angles 10, 10. The front posts, and likewise the rear posts are connected by transverse I-beams 11 and 12 that are disposed in substantially the same horizontal planes as beams 9, 9, although transverse beams 12, 12, are below the horizontal plane of the baking-chamber.

The brick and tile work of the oven 70 closes the metal framework above described, and provides end and side walls about eighteen inches in thickness outside of the same and a roof of about the same thickness above the horizontal plane of the tops of the 75 posts.

Below the baking-chamber, furnaces F are made in the rear of the oven that are of the usual construction so that they can be stoked from the rear. The products of combustion from these furnaces discharge into a series of longitudinal flues 14, 14, 14, 14, which extend forward in the same horizontal plane and discharge into a cross-flue 15. This flue 15 is located back of the vertical plane of the front cross-bars 12 and below the same, and it discharges from its ends into vertical flues 16, 16, that convey the heated products of combustion into the ends of transverse flues 17, 17, that align 90 with each other and extend to within a few inches of the center of width of the oven where they are separated by a comparatively thin brick partition. These transverse flues 17 are situated over the front part of the 95 baking-chamber 0, and the floor thereof consists of a transverse platform 18, which is, preferably, made of cast metal and has its forward edge resting on the rear portion of the inverted channel-beam lintel 19 of the 100

entrance of the baking-chamber and has its ends resting on and built into the side-walls of said chamber.

The baking-chamber is not only heated by the heat derived from the masonry that separates it from the furnaces and flues 14, but derives the larger portion of its heat from the radiation of a series of longitudinally extending pipes 20. These pipes communicate with flues 17 and their front ends are seated in the transverse corrugations of a transversely extending cradle 21, and their rear ends are seated in suitable thimbles 22 in the rear wall of the baking-chamber and discharge into the vertically disposed soot-chamber 23. This soot-chamber is of sufficient width for all of the pipes 20 to discharge into it and said chamber extends upward to about the plane of the underside of the rear cross-beam 11. The wall of the oven back of the soot-chamber is pierced by a series of lined openings 24 that align with pipes 20, and the rear ends of these openings 24 are closed by suitable covers 25, which latter can be removed to permit access to said pipes whenever desired.

The wall immediately in front of transverse flues 17 is also pierced by a series of openings 26 disposed so as to align with pipes 20; and the forward ends of these openings discharge into a transverse dead air-chamber 27, inclosed within said wall, and may be closed by the tubular cover, if desired. A series of longitudinal openings 28 are also made in the front wall of the oven that connect said dead air-chamber with the outer atmosphere, which align with and are greater in transverse dimension than openings 26 so as to permit of the withdrawal therethrough of the covers of the latter when it is desired to have access to pipes 20 or to cross-flue 17. Openings 28 are closed by covers 29, when not in use, and conserve the insulation resulting from the presence of the dead air-chamber.

The upper end of soot-chamber 23 terminates just below the rear cross-beam 11 and discharges into the rear ends of the series of longitudinally disposed pipes 30, 30, the rear portions of which are seated in thimbles 31 built in the rear wall of a reheating chamber 33. This reheating chamber extends horizontally forward through the front wall of the oven and is of the same superficial area as the oven chamber, but is less in height, substantially as shown in the drawings, and the lintel 34 of the entrance thereof is made of a transversely disposed inverted channel-beam whose ends extend to posts 8 and are suitably attached thereto and embedded in the brick work at the sides of the entrance of chamber 33.

Immediately to the rear of lintel 34 a metal platform 35 constitutes the roof of the

heat-chamber. This metal platform consists of a transversely disposed flat plate having several longitudinal ribs depending from its underside, and it is supported by having its ends built in the brick work of the side-walls of the reheating-chamber, and by its forward edge lapping past and resting upon the rear portion of lintel 34.

Pipes 30 form the roof or ceiling of the reheating chamber in the rear of the platform 35, and their forward ends are seated in the corrugations of a cradle 36, which latter corresponds in construction to cradle 21 and rests upon the rear portion of platform 35. Pipes 30 discharge the products of combustion from their forward ends into a cross-flue 37 located immediately back of the front wall of the oven above platform 35, and from this cross-flue 37 said products of combustion discharge into a central flue 38 that extends upward and then longitudinally back over the roof of the oven to the chimney 39.

Lined openings 40 are made in the rear wall of the oven that align with pipes 30 and communicate with the upper end of the soot-chamber 23 and the rear ends of these openings are closed by a suitable removable cap 41. The front wall of the oven is provided with a series of longitudinal openings 42 that align with pipes 30. The rear ends of these openings 42 open into cross-flue 37 and their front ends open into a transversely extending dead air-chamber 43. Between this dead air chamber and the front of the oven there is a series of longitudinal openings 44 which exceed in diameter and align with openings 42. Openings 42 are closed by tubular covers 45 and openings 44 are closed by covers 46, and the relative transverse dimensions of these openings, 42 and 44, are such that when the outer cover 46 is removed cover 45 can be removed by pulling it out through openings 44, thus enabling access to be had to pipes 30.

The entire oven is made of solid brick or tile work between the flues 14 and the baking chamber, between the heating-pipes 20 of the baking-chamber and the reheating-chamber 33, and between pipes 30 of this reheating-chamber 33 and the top or roof of the oven. The rear wall of the oven is also made of brick work or tiling and the presence of soot-chamber 23 therein provides an additional means for retaining the heat within the baking-chamber and the reheating-chamber. The front wall is very thick, but has therein wide entrances or mouths of the baking-chamber and the reheating-chamber.

The entrance of the baking-chamber is closed by a drop-door 47 consisting of a flat plate the upper edge of which is secured to a transverse shaft 51 which is journaled in suitable bearings immediately back of the

forward flange of the lintel 19. This door inclines downward toward the rear at a suitable angle and rests on the sill of the entrance, which latter may be protected by a suitable angle iron 48, if desired. The entrance to the reheating-chamber is closed by a door 49, similar in construction to door 47, and its upper edge is secured to a transverse shaft 50.

10 In front of the oven above the plane of the entrance of the baking-chamber is a transverse shaft 61 the ends of which are journaled in suitable bearings in brackets 62 secured to and projecting forward from

15 the front of the oven. Two large sprocket wheels 63, 63, are mounted on this shaft in front of the ends of the doors 47 and 49, and these sprocket wheels are connected by corresponding endless-chains 64, 64, to 20 smaller sprockets 54 and 55 located in boxes 66 built in the rear-wall of the oven back of the soot-chamber. The upper pair of these sprockets 54 are mounted on a transverse shaft 65 and the lower pair 55 on a trans- 25 verse shaft 55^a, and the ends of these shafts are journaled in vertically disposed bearing- plates 56 the ends of which latter are recessed and adapted to engage guide-rails 57, 57, that extend in the direction of length of 30 the oven and are, preferably, made integral with the top and bottom of boxes 66. These bearing-plates are adjustable forwardly and rearwardly to a limited extent by means of horizontal bolts 58, 58, that extend through 35 enlarged openings in the same and have their inner ends secured in the forward side of the boxes 66, and nuts on their outer ends, and by means of set-screws 60, 60. By prop- 40 erly manipulating the nuts 59 on bolts 58 and screws 60 the chains 64, 64, can be suit- ably tightened.

The lower horizontal stretches of chains 64 extend through suitable recesses in the lower corners of door 47 horizontally 45 through the baking-chamber and within the latter they are connected by transverse trays 72, whose ends are attached to and supported by hangers depending from trucks 69. These trucks comprise a casting which is of 50 an inverted U-shape in cross-section, except at the closed end thereof from which hangers 68 depend, and wheels 70 are placed in the inverted channel of said truck and revolu- 55 bly mounted on shafts 71, which latter have bearings in the side-walls of said chan- nel. These trucks are provided with later- ally projecting studs 72, that are journaled in suitable bearings in every third link of 60 the chains. The two large sprocket wheels 63, 63, are of such diameter that the upper horizontal stretch of the chains 64, 64, ex- 65 tend rearwardly through recesses in door 49 and through the reheating chamber 33, and back through suitable openings in the rear

65 wall of said heating-chamber to and around the small sprockets or wheels 54. The wheels 70 of said trucks travel on longitudinal tracks 75 that extend from the rear wall of the baking-chamber out through the front entrance of the same a suitable distance, and 70 the reheating-chamber 33 is also provided with suitable longitudinal tracks 76 of the same gage as tracks 75, that rest upon the floor of and extend from the rear wall of the reheating-chamber out through the front 75 entrance thereto and have their forward ex- tended ends bent downward, substantially as shown in Fig. 1 of the drawings.

In operation, the trays are loaded with a suitable number of pans of dough and moved 80 by the chains back into the baking-chamber until said baking-chamber is full. The door 47 is then lowered and the pans are left in the oven until the bread is suitably baked. Door 47 is then raised up under the inverted 85 channel lintel 19 whereupon the motion of the chain is reversed, and the pans of baked bread removed from the trays, one after the other, until all of the trays are out of the baking-chamber. As the trays move out of 90 the baking-chamber they are carried by the chains passing around the sprocket 63 up into the reheating chamber 33, and when interred in the latter, door 49 is closed and keeps the trays and the parts of the endless 95 chains supporting the same at such a tem- perature that very little heat is lost when said trays are lowered and loaded, one after the other, with fresh pans of dough and moved back into the baking-chamber again, 100 thus saving considerable time in raising the temperature in the baking-chamber to the necessary degree to bake the bread and in- creasing the output of the oven, while at the same time accomplishing a great saving of 105 fuel.

It will be obvious that changes in the size and dimensions of the various parts of my improved baker's oven can be made, and that under some conditions it might be necessary 110 to modify or omit altogether some of the structural elements, hereinbefore described, without departing from the spirit of my in- vention, as particularly pointed out in the claims. All such modifications and changes 115 I desire to contemplate as coming within the scope of my improvements.

What I claim as new is:

1. A baker's oven comprising a baking chamber, an overhead reheating-chamber, a 120 pair of endless chains, a transverse shaft journaled in front of the oven between the entrances of said baking-chamber and re- heating chamber, large sprocket wheels se- 125 cured on said shaft by means of which alone said chains are conveyed in front of the oven from one chamber to the other, a series of trays adapted to be carried by said

- 4 chains from the reheating chamber to the baking-chamber and vice-versa, and tracks extending longitudinally through the baking and heating chambers upon which the 5 trays are supported and travel when within the chambers; said tracks extending forward beyond the chambers and on opposite sides of the axis of the large sprocket wheels.
2. A baker's oven comprising a baking- 10 chamber, an overhead reheating-chamber, a pair of endless chains, a transverse shaft journaled in front of the oven between the entrances of said baking-chamber and reheating-chamber, large sprocket wheels secured on said shaft by means of which alone 15 said chains are conveyed in front of the oven from one chamber to the other, a series of trays adapted to be carried by said chains from the reheating chamber to the baking- 20 chamber and vice-versa, and longitudinally disposed tracks in said chambers upon which the ends of said trays rest when within the same, and which extend forward beyond said chambers, and the extensions of the 25 upper track curve downward while the extensions of the lower track extend horizontally beneath the large sprocket-wheel and are considerably longer than the curved upper extensions.
3. A baker's oven comprising a baking- 30 chamber, an overhead re-heating-chamber, and a heating system therefor including a longitudinally arranged series of tubular flues constituting part of the ceiling of said 35 baking-chamber, a cradle having a series of corrugations for supporting the ends of the pipes, and a transverse platform upon which the cradle is mounted.
4. A baker's oven comprising a baking- 40 chamber, an overhead re-heating-chamber, and a heating system therefor including a longitudinally arranged series of tubular flues constituting part of the ceiling of the 45 overhead reheating chamber, a cradle having a series of corrugations for supporting the ends of the pipes, and a transverse platform above the entrance of said baking-chamber upon which said cradle is mounted.
5. A baker's oven comprising a baking- 50 chamber, a suitably constructed entrance, a transverse platform extending from side to side of said chamber immediately to the rear of and above said entrance, and a series of longitudinally arranged pipes that constitute part of the heating system of the oven and form part of the ceiling of said chamber and have their rear ends extending into the rear wall of the chamber and their forward ends extending above said platform, a cradle 55 mounted upon the platform having equi-distant corrugations in which the pipe ends are seated.
6. A baker's oven comprising a baking- 60 chamber, a suitably constructed entrance, a transverse platform extending from side to side of said chamber immediately to the rear of and above the entrance of said chamber, and a series of longitudinally arranged pipes that constitute part of the heating system of the oven and form part of the ceiling of said chamber and have their rear ends extending into the rear wall of the chamber and their forward ends extending above said platform, a cradle resting upon said platform and having a series of equi-distant corrugations in which the front ends of said pipes are seated.
7. A baker's oven comprising a plurality of chambers, an inverted channel-iron bridging over each of the entrances thereof, transverse platforms extending from side to side 80 of the chambers the front edges of which lap over and rest upon the rear portions of said channels, transverse flues immediately above said platforms, a vertically elongated soot-chamber in the rear wall of said oven 85 and series of longitudinally arranged pipes the forward ends of which are supported by said platform which connect said transverse flues and soot-chamber and constitute part of the ceiling of said chambers. 90
8. A baker's oven comprising a plurality of chambers, an inverted channel-iron bridging over each of the entrances thereof, transverse platforms extending from side to side 95 of the chambers the front edges of which lap over and rest upon the rear portions of said channels, transverse flues immediately above said platforms, a vertically elongated soot-chamber in the rear wall of said oven, a cradle supported upon said platform, and 10 series of longitudinally arranged pipes the forward ends of which are seated in said cradle which connect said transverse flues and soot-chamber and constitute part of the ceiling of said chambers. 10
9. A baker's oven comprising a plurality of chambers, an inverted channel-iron bridging over each of the entrances thereof, transverse platforms extending from side to side 11 of the chambers the front edges of which lap over and rest upon the rear portions of said channels, transverse flues immediately above said platforms, a vertically elongated soot-chamber in the rear wall of said oven, a cradle supported upon said platform, series of longitudinally arranged pipes the forward ends of which are seated in said cradle which connect said transverse flues and soot-chamber and constitute part of the ceiling of said chambers, and closed openings in the front wall of the oven in alignment with said pipes that permit access thereto. 11
10. A baker's oven comprising a plurality of chambers, an inverted channel-iron bridging over each of the entrances thereof, transverse platforms extending from side to side 1 of the chambers the front edges of which

lap over and rest upon the rear portions of said channels, transverse flues immediately above said platforms, a vertically elongated soot-chamber in the rear wall of said oven, 5 a cradle supported upon said platform, series of longitudinally arranged pipes the forward ends of which are seated in said cradle which connect said transverse flues and soot-chamber and constitute part of the 10 ceiling of said chambers, and closed open-

ings in the front and rear walls of the oven in alinement with the pipes and permit access thereto.

In witness whereof I have hereunto set my hand this 8 day of June, 1915. 15

WILLIAM FERDINAND PETERSEN.
